UNITED STATES PATENT OFFICE.

CLARENCE D. OVERSMITH, OF LIMA, OHIO.

DESIGN FOR AN ADVERTISING DISPLAY-CASE.

53,688.

Specification for Design.

Patented Aug. 5, 1919.

Application filed March 15, 1919. Serial No. 282,985. Term of patent 14 years.

To all whom it may concern:

Be it known that I, CLARENCE D. OVERSMITH, a citizen of the United States, residing at Lima, in the county of Allen and State of Ohio, have invented a new, original, and ornamental Design for an Advertising Display-Case, of which the following is a specification, reference being had to the accompanying drawing, forming part thereof.

The figure is a front elevation of my case. It comprises a vertical body of rectangular section resting upon a rectangular pedestal with a paneled base and having a concave molding upon the base with a convex molding or quarter round between the concave molding and the body. In addition to the advertising matter intended to be carried in the blank spaces shown upon the front of

the body, my case is intended to carry a thermometer, barometer, and a clock. The body is provided with a capital formed or molded as shown in the drawing, surmounted by a curved cap piece of the outline shown, while brackets are secured at the top of the body at each side to support the capital and the cap piece.

I claim:

The ornamental design for an advertising display case, as shown and described.

In testimony whereof I affix my signature in the presence of two witnesses.

CLARENCE D. OVERSMITH.

Witnesses:

R. CLAUSSSEN,
HERBERT E. SITZ.
